UNITED STATES PATENT OFFICE.

ARTHUR PEART HOLDEN AND PHILIP MORGAN, OF TORONTO, ONTARIO, CANADA,
ASSIGNORS TO THE HOLDEN-MORGAN COMPANY, LIMITED, OF TORONTO, ONTARIO,
CANADA, A CORPORATION OF ONTARIO.

FOLDER FOR WRAPPING-MACHINES.

1,085,258.

Specification of Letters Patent.

Patented Jan. 27, 1914.

Application filed May 5, 1913. Serial No. 765,616.

To all whom it may concern:

Be it known that we, ARTHUR PEART HOLDEN and PHILIP MORGAN, of the city of Toronto, in the county of York and Province of Ontario, Dominion of Canada, have invented certain new and useful Improvements in Folders for Wrapping-Machines; and we hereby declare that the following is a full, clear, and exact description of the same.

Our invention relates to an end folder which will uniformly shape the end folds of a tubular wrapper irrespective of the uniformity of shape or size of the article it contains, and the object of our invention is to so construct and operate the end folder that it will exteriorly engage one side of the wrapper and fold that side against the article, and then interiorly engage the wrapper and simultaneously fold all the remaining sides to effect the sealing of the package ends; the folder during such interior engagement with the wrapper operating as a former to define the lines along which the folds are made.

In the drawings:—Figure 1 is an elevation of a folder; Fig. 2 is a plan view of the construction shown in Fig. 1; Fig. 3 is an elevation of the folder shown in Fig. 1 with its parts in their contracted position; Fig. 3^a is a perspective view of a partly-wrapped package showing the formation of the fold when the folder parts are in the position shown in Fig. 3; Fig. 4 is an elevation of the folder shown in Figs. 1 and 3 with its parts in the position shown in Fig. 1; Fig. 4^b is a perspective view of a wrapper showing the formation of the folds when the folder parts have assumed the position shown in Fig. 4; Fig. 4^b is a perspective view of the wrapper when the peak folds have been closed against the ends of the package, the closing of the peak folds, however, being by means supplemental to the folder; Fig. 5 is an elevation of a modification of the folder shown in the preceding views with its parts in their contracted position, this folder forming the same style of fold as that shown in Figs. 3^a and 4^a; Fig. 5^a is a perspective view of a wrapper showing the formation of the folds when the folder parts are in the position shown in Fig. 5; Fig. 6 is a similar view to Fig. 5 with the folder parts in their extended posi-

tion; Fig. 6^a is a perspective view of a wrapper showing the folds when the folder parts are in the position shown in Fig. 6; Fig. 6^b is a perspective view of the wrapper with its ends sealed; and, Fig. 7 is a similar view to Fig. 6 showing the same style of folder as shown in the preceding view, with a slight change in the conformation of the fold-forming parts.

The folders hereinafter described and illustrated in the accompanying drawings have been particularly designed for use in connection with a wrapping machine in which the articles to be wrapped may be either of a uniform or non-uniform shape and size, and are the result of a series of exhaustive experiments with regard to the formation of the end folds of a wrapper containing an irregular-shaped package, we having discovered during these experiments that it was necessary to construct and arrange the folder so that it would exteriorly engage and fold one side of the wrapper and then interiorly engage and support the remaining sides of the wrapper during the formation of the remainder of the folds, and during such interior engagement, define the lines of said folds.

The folder shown in Fig. 1 consists of a substantially rectangular fold-forming element *f* and two fold-forming elements *f'* hingedly connected to the sides of the fold-forming element *f* and extending to the top thereof. The fold-forming elements *f'* are so hinged to the fold-forming element *f* that they can be turned to lie flat against the fold-forming element *f*, or approximately so, as shown in dotted lines in Fig. 1 and in full lines in Fig. 3, or extended into the same plane as the fold-forming element *f*, as shown in full lines in Figs. 1 and 4. Each of the fold-forming elements *f'* is provided with a rod *g*, at the lower end of each of which is a pinion *h* engaged by a reciprocating rack *i*, the movement of which turns the fold-forming elements *f'* to lie against the fold-forming element *f*, as shown in Fig. 3, or to extend the fold-forming elements *f'* into the same plane as the fold-forming element *f*, as shown in Figs. 1 and 4.

When the folder shown in Figs. 1, 2, 3 and 4 is brought into operative relation with the wrapper, the fold-forming element

f exteriorly engages the side *j* of the wrapper and folds it to lie against the end of the article as shown in Fig. 3^a. The top edges of the fold-forming element *f*, when the 5 folder has reached its limit of movement, is approximately opposite the top of the article and interiorly in contact with the side *j'* of the wrapper, and in this position, its side edges *p'* are interiorly in engagement with the wrapper sides *j''* to define the 10 lines of the folds. When the fold-forming element *f* has reached its limit of movement, the rack *i* is operated to cause the pinions *h* and rods *g* to oscillate the fold-forming elements *f'* from the position 15 shown in dotted lines in Fig. 1 and full lines in Fig. 3 to the position shown in full lines in Figs. 1 and 4, the fold-forming elements *f'* as they move to this latter position, engaging the sides *j''* to complete the formation 20 of the peak folds *k* which, in this case, are located at the vertical sides of the wrapper. The edges *f''* of the fold-forming elements *f'* are inclined to correspond with 25 the inclination of the sides of the peak folds *k*. In fact, the fold-forming elements *f'* may be of a triangular shape, as indicated by the dotted lines *m''* joining the sides *f''* with the bottoms of said elements. During 30 the movement of the fold-forming elements *f'* from their normal position to their extended position, they press interiorly against the sides *j''* and tension the wrapper as they draw the sides of the wrapper to the peak 35 folds *k*, the fold-forming element *f* during this action of the fold-forming elements *f'*, serving as an interior former and support for the wrapper folds.

In Figs. 5 and 6, the fold-forming elements *l*, *l'* are similar to the fold-forming 40 elements *f*, *f'*, but instead of the fold-forming elements *l*, *l'* being oscillatingly hinged, they have a reciprocating movement with relation to the fold-forming element *l*, this 45 movement being provided by the triangular guide slots *l''* in the fold-forming element *l* and the guide pins *m* for the fold-forming elements *l'* operating in said slots. The 50 style of the fold and the method of making it are the same as in regard to the folders shown in Figs. 1, 2, 3 and 4. In Figs. 5 and 6, the fold-forming elements *l'* are 55 shown to be provided with inclined sides *m'*, but as in the previous case, these fold-forming elements may be of a triangular shape, as indicated by the dotted lines *m''* in those views.

In Fig. 7, the folder is similar to that shown in Figs. 5 and 6 and operated in the 60 same way, but the fold-forming elements *o'* have curved sides *o''*.

The above description may be briefly summarized as follows:—By making a folder of two or more fold-forming elements 65 movable into a contracted position when the

folder comes into operative relation with the wrapper, it is possible to enable the folder to exteriorly engage one side of the wrapper and fold it to the article, then interiorly engage the wrapper, and by the 70 expansion of its component parts, effect the formation of a plural number of folds and complete, at a single operation of the folder, the closing of the end of the wrapper preparatory to the peak fold or folds being 75 sealed, one of the fold-forming elements during such action, defining the lines of the folds and serving as a former and support therefor.

Having thus fully described the nature 80 of our invention, what we claim as new and desire to secure by Letters Patent, is:—

1. A folder comprising a fold-forming element to exteriorly engage and fold one side of a tubular wrapper and then enter 85 interiorly of its remaining sides to define the lines along which they are to be folded, and a plurality of fold-forming elements co-operating therewith to enter interiorly of the wrapper for the formation of the folds 90 along the lines so defined.

2. A folder comprising hingedly-connected fold-forming elements relatively movable with respect to each other whereby one of said fold-forming elements will exteriorly engage and fold one side of a tubular wrapper and then enter interiorly of its remaining sides to define the lines along which they are to be folded, and actuating means for said fold-forming elements changing their 100 normal relations whereby during such change the other fold-forming elements will interiorly engage the remaining wrapper sides and fold them along the lines so defined.

3. A folder comprising a fold-forming element to close one side of a tubular wrapper and then enter interiorly of its remaining sides to define the lines of the folds and serve as a former and support therefor, and 110 fold-forming elements co-operating therewith to interiorly engage the wrapper and, by tensioning it, effect the formation of the folds along the lines so defined.

4. A folder comprising a relatively fixed 115 element, movable elements co-operating therewith, and actuating means therefor whereby the folder will exteriorly engage and fold one side of a tubular wrapper and then enter interiorly of its remaining sides 120 to define the lines along which they are to be folded, and then, by interiorly engaging said remaining sides, fold them along the lines so defined.

5. A folder comprising a relatively fixed 125 member, movable members hingedly connected thereto and normally inoperative as the folder comes into engagement with the wrapper, and means to bring the movable members into operative relation with the 130

- fixed member whereby said folder will complete the formation of a plural number of folds at a single operation.
6. A folder comprising relatively fixed and movable elements hingedly connected to exteriorly engage and fold one side of a tubular wrapper and then enter interiorly of its remaining sides to define the lines along which they are to be folded, and means actuating the movable elements whereby the folder will engage the remaining wrapper sides and fold them along the lines so defined.
7. A folder comprising fixed and movable elements normally in contracted relation whereby the folder will exteriorly engage and fold one side of the wrapper and then enter interiorly of it to define the lines along which the remaining sides are to be folded, and means for bringing said movable elements into expanded relation whereby they will interiorly engage the wrapper and fold the remaining sides along the lines so defined.
8. A folder comprising fixed and movable elements normally in contracted relation whereby the folder will exteriorly engage and fold one side of the wrapper, said movable elements having convergent sides, and means for bringing said movable elements into expanded relation whereby they will interiorly engage the wrapper and fold the remaining sides along the lines so defined.
9. A folder comprising a relatively fixed element, and movable elements hingedly connected thereto in contracted relation to exteriorly engage and fold one side of a tubular wrapper and then enter interiorly of its remaining sides to define the lines along which they are to be folded, and means actuating the movable elements whereby the folder will engage the remaining wrapper sides and fold them along the lines so defined.
10. A folder comprising a relatively fixed element, and movable elements coöperating therewith, said elements being in contracted relation when the folder engages the wrapper, whereby the folder will exteriorly engage and fold one wrapper side and then enter interiorly of its remaining sides to define the lines along which they are to be folded, and means for bringing the movable elements into expanded relation with the relatively fixed element whereby they will interiorly engage the remaining wrapper sides and fold them along the lines so defined.
11. A folder comprising a relatively fixed element, and movable elements normally in contracted relation when the folder engages the wrapper, whereby the folder will exteriorly engage and fold one side of the wrapper and then enter interiorly of it, and means for bringing the movable elements into expanded relation with the relatively fixed element whereby the folder will, at a single operation, complete the formation of a plural number of folds, said movable elements having convergent sides.
12. A folder comprising a relatively fixed element, and movable elements angularly disposed thereto, with means for bringing the movable elements into substantially the same plane as the relatively fixed element when the folder engages the material, whereby the folder will, at a single operation, complete the formation of a plural number of folds.
13. A folder comprising a relatively fixed element, and movable elements angularly disposed thereto having convergent sides with means for bringing the movable elements into substantially the same plane as the relatively fixed element when the folder engages the material, whereby the folder will, at a single operation, complete the formation of a plural number of folds.
14. A folder comprising a relatively fixed element, and movable elements hingedly connected thereto, said movable elements being inoperative when the folder engages the material, and means for then bringing the movable elements into operative relation, whereby the folder will, at a single operation, complete the formation of a plural number of folds.
15. A folder comprising a relatively fixed element, and movable elements hingedly connected thereto, said movable elements being angularly disposed to the relatively fixed element when the folder engages the material, said movable elements having convergent sides, and means for bringing the fold-forming elements into substantially the same plane as the relatively fixed element whereby the folder will, at a single operation, complete the formation of a plural number of folds.
16. A folder comprising a relatively fixed element, and movable elements angularly disposed thereto and normally inoperative when the folder engages the wrapper, and means for rendering the movable elements operative, whereby the folder will, at a single operation, complete the formation of a plural number of folds.
17. A folder comprising a relatively fixed element, and movable elements angularly disposed thereto and normally inoperative when the folder engages the wrapper, and means for bringing the movable elements into operative relation with the relatively fixed element, whereby the folder will, at a single operation, complete the formation of a plural number of folds, said fold-forming elements having convergent sides.
18. A folder consisting of a relatively fixed element, and movable elements hinged thereto and normally occupying an inclined

position with relation to the plane of the relatively fixed element, and means for moving the movable elements into substantially the same plane as the relatively fixed element, whereby the folder, at a single operation, will complete the formation of a plural number of folds.

19. A folder consisting of a relatively fixed element, and movable elements hinged thereto and normally occupying an inclined position with relation to the plane of the relatively fixed element, said movable elements having convergent sides, and means for moving the movable elements into substantially the same plane as the relatively fixed element, whereby the folder, at a single operation, will complete the formation of a plural number of folds.

20. A folder consisting of a substantially fixed element, and a plural number of movable elements oscillatingly connected thereto and normally occupying inclined positions

with relation to the plane of the relatively fixed element, and means for actuating said movable elements, whereby said folder will, at a single operation, complete the formation of a plural number of folds.

21. A folder consisting of a substantially fixed element, and a plural number of movable elements oscillatingly connected thereto and normally occupying inclined positions with relation to the plane of the relatively fixed element, said movable elements having convergent sides, and means for actuating said movable elements, whereby said folder will, at a single operation, complete the formation of a plural number of folds.
